UNITED STATES PATENT OFFICE.

CHARLES G. STRUBLER, OF TECUMSEH, MICHIGAN.

SCALE-LOOP.

SPECIFICATION forming part of Letters Patent No. 579,192, dated March 23, 1897.

Application filed February 27, 1896. Serial No. 581,067. (No model.)

To all whom it may concern:

Be it known that I, CHARLES G. STRUBLER, a citizen of the United States, residing at Tecumseh, in the county of Lenawee and State 5 of Michigan, have invented certain new and useful Improvements in Scale-Loops; and I do hereby declare the following to be a full, clear, and exact description of the invention, such as will enable others skilled in the art 10 to which it appertains to make and use the same.

My invention relates to improvements in a scale-loop having a block-bearing journaled in the ends of a loop-shaped band or clip; 15 and the objects of my improvements are, first, to provide means for the perfect adjustment of the loop-bearing to the knife-edges or the pivot of the scale; second, to afford facilities for changing the length of the 20 loop and the form of the bearing-block; third, to reduce the friction upon the scale-levers. I attain these objects by the mechanism illustrated in the accompanying drawings, in which—

25 Figure 1 is the front elevation. Fig. 2 is the side elevation. Fig. 3 is a top view. Fig. 4 is a detailed view in perspective of the loop and block. Fig. 5 is a front elevation of a double bearing-loop. Fig. 6 is a side elevation of same. Fig. 7 is a front elevation of beam-loop. Fig. 8 is a side elevation of same.

Similar letters refer to similar parts throughout the several views.

The band A, blocks B, and journal D constitute the scale-loop.

The block B (shown in Fig. 1) is vertically adjustable on the journal D. It is channeled or grooved on both top and bottom and is journaled nearer the bottom of one groove 40 than the other. Thus it will be seen that by revolving the block B a half-turn upon its axis will change the inside dimensions of the loop. This feature is very desirable in making a ready adjustment where it is necessary 45 to have the loops in a scale of different lengths.

In Fig. 2 is shown a side elevation of block B. The dotted lines show the block tilted to one side. The object of this tilting movement is to secure a perfect adjustable non- 50 friction bearing-surface for the scale-pivot.

If desirable, the block B can be made flat on the top and grooved on the bottom, or it can be V-shaped on one face and concave on the other. I prefer, however, to have both 55 sides grooved the same. The journal can also be placed in the center of the block B, if desired. By this construction when the blocks get cut or worn in course of use they can be turned a half-turn and the unused 60 surface brought forward for the pivot to work on.

In Fig. 5 is shown a double bearing-loop having two block-bearings, one at each end, with a scale-pivot C resting on each as it 65 would be when in actual use. The upper block is shown in section, showing the journal D.

In Fig. 6 is shown another view of Fig. 5, leaving out the pivots C. The lower block is shown in dotted lines tilted to one side, as it 70 would be if the scale-pivot was out of alignment.

Figs. 7 and 8 represent two views of loop having my journaled blocks. Fig. 7 shows the block B in section, the remaining part of 75 block resting on the pivot C.

I do not confine myself to the shapes of the band or loop or the shape of the block. The band could be of such shape and bent in such a way as to form the journals D out of the 80 same piece, if desired.

I claim—

1. In a scale-loop the combination with a suitable band of connecting bearing-blocks pivotally mounted having free bearing-surfaces on both sides, substantially as described.

2. In a scale-loop the combination with a suitable band of a connecting bearing-block pivotally mounted in the ends of said band, 90 substantially as described.

3. In a scale-loop the combination with a suitable band of a connecting bearing-block pivotally mounted approximately midway its upper and lower surface, substantially as 95 described.

In testimony whereof I affix my signature in presence of two witnesses.

CHARLES G. STRUBLER.
